US00D752078S

(12) **United States Design Patent**
Guesnon, Jr.

(10) **Patent No.:** **US D752,078 S**
(45) **Date of Patent:** **** Mar. 22, 2016**

(54) **DISPLAY SCREEN OR PORTION THEREOF
WITH GRAPHICAL USER INTERFACE**

(71) Applicant: **Thales Avionics, Inc.**, Irvine, CA (US)

(72) Inventor: **Andrew A. Guesnon, Jr.**, Anaheim Hills, CA (US)

(73) Assignee: **THALES AVIONICS, INC.**, Irvine, CA (US)

(**) Term: **14 Years**

(21) Appl. No.: **29/468,831**

(22) Filed: **Oct. 3, 2013**

(51) LOC (10) Cl. **14-04**

(52) U.S. Cl.

USPC **D14/486**

(58) **Field of Classification Search**
